US00D885889S

(12) **United States Design Patent** (10) **Patent No.:** **US D885,889 S**
(45) **Date of Patent:** **** Jun. 2, 2020**

(54) **BLANK FOR SHIPPER INSERT**

(71) **Applicant:** **INTERNATIONAL PAPER COMPANY**, Memphis, TN (US)

(72) **Inventor:** **Kent Owen Nelson**, Lees Summit, MO (US)

(73) **Assignee:** **INTERNATIONAL PAPER COMPANY**, Memphis, TN (US)

(**) **Term:** **15 Years**

(21) **Appl. No.:** **29/656,828**

(22) **Filed:** **Jul. 17, 2018**

(51) **LOC (12) Cl.** **09-03**

(52) **U.S. Cl.** **USPC** **D9/433**

(58) **Field of Classification Search**

USPC ..... D6/300, 308, 546, 672, 675, 678.2; D7/300, 305, 306, 307, 308, 312, 313, D7/391, 397, 541, 550.1, 553.1, 553.2, D7/553.3, 555.589, 590, 601, 602, 701; D9/414, 415, 418, 420, 424, 425, 426, D9/430, 432, 433, 434, 455, 456, 457, D9/499, 721, 722, 737, 756, 759, 760, D9/761, 612, 653, 661, 667, 674; D19/3, D19/75, 107; D20/11, 14, 19, 21, 22, 27, D20/40, 42, 43, 44; D14/300, 308, 313, D14/314, 348-356, 441-446, 489, 491, D14/492, 494, 495; D5/6, 7, 11, 23, 25, D5/26, 37, 45, 56, 57, 58, 59.6, 61, 62 CPC A47J 47/20; B65D 21/083; B65D 21/086; B65D 57/00; B65D 61/02; B65D 81/133; B65D 81/027; B65D 5/01; B65D 5/02; B65D 5/0254; B65D 5/0045; B65D 5/18; B65D 5/2033; B65D 5/38; B65D 5/40; B65D 5/48038; B65D 5/48032; B65D 5/48004; B65D 1/24; B65D 1/34; B65D 1/38; B65D 1/335; B65D 77/24; B65D 77/067; B65D 5/00-02; B65D 5/0209-0272; B65D 5/029; B65D 5/72; B65D 5/541; B65D 5/705; B65D 5/706;

(57)

CLAIM

The ornamental design for a blank for shipper insert, as shown and described.

DESCRIPTION

The sole FIGURE is a top plan view of a blank for shipper insert of the present invention.

The broken lines are shown for the purpose of illustrating exemplary fold lines for assembly of the blank for shipper and form no part of the claimed design.
